United States Patent

Des. 237,625
Patented Nov. 11, 1975

237,625

TELEPHONE INTERCOMMUNICATING UNIT

Arnold Wolf, Los Angeles, Bruce A. Buell, Walnut Creek,
and William E. Howe, Orinda, Calif., assignors to
Voycall, Oakland, Calif.

Original design application July 3, 1972, Ser. No.
268,543, now Patent No. 231,740. Divided and
this application Jan. 21, 1974, Ser. No. 434,918

Term of patent 14 years

Int. Cl. D14—03

U.S. Cl. D26—14 A

FIG. 1

FIG. 2

FIG. 1 is a perspective view of one embodiment of a telephone intercommunicating unit according to the new design; and

FIG. 2 is a perspective view of another embodiment of the telephone intercommunicating unit according to the new design.

This is a division of design application Ser. No. 268,543, filed July 3, 1972 and now Pat. No. D-231,740.

We claim:

The ornamental design for a telephone intercommunicating unit, as shown and described.
